UNITED STATES PATENT OFFICE.

GEORGE WHITTAKER HARGREAVES, ALBERT HARGREAVES, AND ROBERT HARGREAVES, OF BLACKBURN, ENGLAND.

CARDING-ENGINE.

1,310,827.

Specification of Letters Patent. Patented July 22, 1919.

Application filed October 15, 1917. Serial No. 196,587.

To all whom it may concern:

Be it known that we, GEORGE WHITTAKER HARGREAVES, ALBERT HARGREAVES, and ROBERT HARGREAVES, all subjects of the King of Great Britain, residing at Brookhouse Lane, Blackburn, in the county of Lancaster, England, have invented certain new and useful Improvements in Carding-Engines, of which the following is a specification.

10 This invention relates to carding engines and has for its chief object to provide an improved arrangement for simplifying and facilitating the stripping, cleaning and grinding operations which will dispense 15 with the necessity for transferring the stripping brush from the cylinder to the doffer to perform the stripping operations and in like manner the grinding roller from the cylinder to the doffer to perform the grinding 20 operation thereby reducing labor.

According to this invention means are provided for detachably mounting the stripping brush in the throat formed by the doffer or cylinder and for moving same into 25 contact with the wire of the card clothing on the doffer and cylinder for stripping purposes and for raising such brush out of contact therewith after the stripping operation has been effected or for cleaning purposes, 30 the said brush being advantageously inclosed within an air tight or closely fitting casing adapted to be connected with an air suction plant for dust removing purposes.

In the accompanying drawings:—

35 Figure 1 is an end elevation of part of a carding engine fitted with a stripping brush and casing in accordance with this invention.

Fig. 2 is a front view of one end of the 40 apparatus, and Fig. 3 is an end view of the casing.

A indicates the stripping brush, B the cylinder, C the doffer and D the casing.

The invention may be carried out in various 45 ways and in the form of apparatus shown, two end frames *d* shaped to the curves of the doffer and cylinder frames *b* and *c* are bolted or otherwise attached thereto. Each of these end frames has a curved 50 outer portion of a somewhat larger radius than that of the stripping brush and the frames are formed with slots *d*¹ for the insertion and removal of the brush spindle *a*, slides *d*² being employed to close the greater 55 portion of said slots but leave a space *d*³

for the lifting and lowering movement of the spindle. The latter is conveniently supported at its end in a bearing *a*¹ formed in a slide or arm *a*² that is slidable in a bracket *a*³ which is adjustably mounted on one of the existing cylinder blocks *b*¹. Each slide or arm is formed with a slotted cross slide *a*⁴ for a block *a*⁵ adapted to be engaged by an eccentric pin *a*⁶ on the end of a shaft *a*⁷ which extends between and through the end frames *d* and is fitted with one or more handles *a*⁸ for turning purposes, the arrangement being such that when the handle is turned in one direction the eccentrics lower the slides or arms *a*² to bring the stripping 65 brush into simultaneous engagement with the card wire of the cylinder and the doffer, and when turned in the other direction raise the stripping brush clear of such wire. To cause the stripping brush to engage equally 70 with the wire on the cylinder and doffer the slide or arm *a*² is made extensible at *a*⁹ and provided with screw adjustment *a*¹⁰ and the bracket which carries such arm is slidable on the cylinder block *b*¹ for moving the stripping 75 brush *A* toward the cylinder or doffer as may be required, said movement being conveniently effected by an adjusting screw *b*². The space between the end frames is covered by the cylinder and doffer plates 80 *d*⁴ *c*¹ with the exception of an aperture *d*⁵ which is large enough to admit a cylindrical member which may be either the stripping brush or a grinding roller substituted therefor, and is normally closed by a curved door 85 *d*⁶ which fits closely over the end frame and along the adjacent edges of the cover plates *d*⁴ *c*¹. This door is advantageously hinged along its lower edge to the adjacent plate and a convenient method of cleaning the 90 stripping brush comprises a comb *a*¹¹ which may be hinged coaxially with the door, and adapted to swing independently of the door, so that the comb may be moved into contact with the brush for cleaning purposes when 95 the door is opened.

By the arrangement described all that is necessary to perform the stripping operation is to turn the handle *a*⁸ to lower the brush into the wire of the doffer and cylinder and put the rope or belt onto the pulley on the stripping brush spindle, one of such pulleys being conveniently mounted at each end of the spindle. When the stripping operation is completed the brush is raised out of the 105 110

wire and if it is desired to clean it the door is opened and the brush turned in the opposite direction so that the backs of the wire run in contact with the stripping comb, and as the latter is situated at the juncture of the hinge the material from the brush is transferred onto the open door. To effect the grinding operation the brush is removed and a grinding roller substituted therefor, any adjustments that may be required being effected by the adjusting screws on the arms and brackets previously described. The cover plate or end frame is advantageously fitted with a pipe connection d^7 (Fig. 3) so that if it is desired to use the apparatus in conjunction with a suction dust removing plant it only becomes necessary to connect a flexible or other pipe with the aforesaid pipe connection, the cover plate and end frames being constructed to make as tight a fit as is practicable with the adjacent stationary and moving parts of the carding engine.

The wires of the stripping roller A are inclined forward in the direction of rotation of the roller as shown by dotted lines in Fig. 1, and are made of sufficient length to enable them to act as hooks which remove fiber simultaneously from the cylinder B and doffer C, and retain the fiber until it is removed by the comb a^{11} . Heretofore, the stripping roller or brush has been used first to strip one of the members A, C, and then transferred to the other member to strip the latter.

What we claim as our invention and desire to secure by Letters Patent in the United States is:—

1. In stripping brush apparatus for a carding engine having a doffer and a cylinder forming a throat, a cylindrical stripping brush, means for adjustably mounting the stripping brush in said throat, and means for moving such brush into and out of simultaneous contact with the carding surfaces of the doffer and cylinder.

2. In a carding engine having a cylinder and a doffer forming a throat, means for adjustably and detachably mounting a cylindrical member which may be either a stripping brush or a grinding roller in said throat, and means for moving such member into and out of simultaneous contact with the carding surfaces of the doffer and cylinder.

3. In stripping brush apparatus for a carding engine having a doffer and a cylinder forming a throat, a cylindrical stripping brush, means for adjustably mounting the stripping brush in said throat, a closely fitting casing adapted to inclose the brush, and means for moving the latter into and out of simultaneous contact with the carding surfaces of the doffer and cylinder.

4. In stripping brush apparatus for a

carding engine having a doffer and a cylinder forming a throat, a cylindrical stripping brush, means for adjustably and detachably mounting the stripping brush in said throat, a closely fitting casing adapted to inclose the brush and to be connected with an air suction plant, end slots and slides in the ends of the casing to permit the insertion and removal of the brush and to permit its lifting and lowering movements and means for moving the brush into and out of simultaneous contact with the carding surfaces of the doffer and cylinder.

5. In stripping brush apparatus for a carding engine, the combination of a stripping brush, a casing therefor and a stripping comb connected with the casing and adapted to be moved into and out of contact with the stripping brush.

6. In stripping brush apparatus for a carding engine, having a cylinder and a doffer forming a throat, means for adjustably and detachably mounting a cylindrical member in said throat, said means comprising slidable brackets situated at opposite ends of the cylinder casing, means for adjusting each bracket toward the cylinder or doffer, an extensible arm slidably mounted in each bracket and having a bearing for a rotatable spindle, a transverse slide formed in each arm, a block engaging each slide, an eccentrically mounted pin passing through each block, a shaft connecting said pins, means for turning said shaft to move the extensible arm to either end of its traverse and means for retaining the arm in position in relation to its bracket.

7. In stripping brush apparatus for a carding engine having a cylinder, a doffer, and a cylindrical stripping brush, the combination with said parts of slidable brackets situated at opposite ends of the cylinder casing, means for adjusting each bracket toward the cylinder or doffer, an extensible arm slidably mounted in each bracket and having a bearing adapted to be slid over the end of the stripping brush spindle, means for retaining said bearing in position upon the spindle, a casing adapted to inclose the brush and enable it to be moved into and out of engagement with the carding surfaces on the cylinder and doffer, a lid adapted to cover and uncover an aperture in the casing through which the brush can be inserted and removed, a transverse slide formed in each extensible arm, a block engaging each slide, an eccentrically mounted pin passing through each block, a shaft connecting said pins and supported in bearings in the casing, and means for turning said shaft to put the brush into and out of simultaneous engagement with the carding surfaces on the cylinder and doffer.

8. In stripping brush apparatus for a carding engine having a cylinder, a doffer,

- and a cylindrical stripping brush, the combination with said parts of slideable brackets situated at opposite ends of the cylinder casing, means for adjusting each bracket toward the cylinder or doffer, an extensible arm slidably mounted in each bracket and having a bearing adapted to be slid over the end of the stripping brush spindle, means for retaining said bearing in position upon the spindle, a casing adapted to inclose the brush and enable it to be moved into and out of engagement with the carding surfaces on the cylinder and doffer, a lid adapted to cover and uncover an aperture in the casing through which the brush can be inserted and removed, a transverse slide formed in each extensible arm, a block engaging each slide,

an eccentrically mounted pin passing through each block, a shaft connecting said pins and supported in bearings in the casing, means for turning said shaft to put the brush into and out of engagement with the carding surfaces on the cylinder and doffer, and a stripping comb connected with the casing and adapted to be moved into and out of contact with the stripping brush.

In testimony whereof we affix our signatures in the presence of two witnesses.
